UNITED STATES PATENT OFFICE.

WILLIAM A. LINDAUER, OF EL PASO, TEXAS.

FLUID-CONDITIONING APPARATUS.

1,379,831.

Specification of Letters Patent. Patented May 31, 1921.

Application filed June 28, 1918. Serial No. 242,358.

To all whom it may concern:

Be it known that I, WILLIAM A. LINDAUER, citizen of the United States, residing at El Paso, in the county of El Paso and State 5 of Texas, have invented certain new and useful Improvements in Fluid-Conditioning Apparatus, of which the following is a specification.

The object of this invention is to provide new and improved means for moistening and cooling air, also to provide for the collection and accumulation of the cooling liquid, generally water, that it may be held stored for any use for which it is applicable. 10 In its broader aspects the invention is capable of many applications, such for instance as to effect the requisite cooling of water in radiators of automobiles or for the immediate cooling of liquids circulating in the 15 water jackets of internal combustion engines, or for the cooling of rapid fire guns, or it may be applied for the purposes of refrigeration in refrigerating plants, or for cooling in ventilating systems.

20 In the accompanying specification the disclosure is of a preferred embodiment applied to a ventilating fan of the ordinary electric motor driven type, the fan shown being of the oscillating type.

25 In the drawings accompanying and forming part of this disclosure:—Figure 1 is a side elevation of the electric fan with my device applied thereto. Fig. 2 is a view on line 2—2 of Fig. 1 in the direction indicated by the arrow. Fig. 3, is an enlarged detail view of parts in section. Fig. 4 is a detail of part of the outermost ring, its discharge mechanism and the collecting box or shell. Fig. 5 is a view of a modification of 30 the outer ring and collecting shell. Fig. 6 is a view showing the application of the device to a fan adjustable in a vertical plane.

As the details of the fan and motor may be of any of the well known types a particular description of the same is deemed unnecessary.

As shown the motor proper is indicated at 1, the same being mounted on any proper base 2, the motor shaft 3, carrying a fan 4 of any desired number of radial blades projecting from a central boss secured on the motor shaft. The fan as is usual is protected by a wire guard 5 rigidly secured to the motor casing and of a size to extend 55 around and in front of the fan. As stated

all these parts may be of the usual construction except when, as hereinafter described, such changes are made as are necessary to permit of the application of the following construction forming the preferred embodiment of my invention, which comprises:—a ring 11 which may be of metal, vulcanite or any other suitable material and which is in section of broadly V shape carrying a central groove or channel 12 as shown in Fig. 3. This 60 outer ring is preferably of a diameter nearly that of the fan and is rigidly secured to the rear of the fan blades by brackets 10. It is obvious, however, that the brackets may be secured on the front of the fan, and the 65 series of rings carried on the face of the fan, and this arrangement is preferable in some uses to be hereinafter stated.

The V shaped sides of the ring incline inwardly on each side of the central groove 70 and the outer edges are bent sharply inward as flanges 13. Inclosed within the outer ring 11 and supported therefrom by radial strips 14 are a series of spaced rings 15, 15^a, 15^b and 15^c. These rings are of any suitable 75 material, as metal, rubber or the like, and are of a width equal to that of the outer ring and like such outer ring have their edges bent sharply inward to form like flanges. Each inner ring is of substantially 80 the same diameter for its entire width except for the series of grooves 16 formed in the ring and extending for the width of the ring, so that in cross section the rings appear corrugated as shown in Fig. 3. Each 85 ring also at the bottom of each groove is perforated by a series of openings 17 of relatively small diameter. Care must be exercised that the series of inner rings are rigidly supported within the outer ring and 90 for such purpose additional securing strips similar to 14 may extend from both sides or edges of the outer ring, the strips being securely fastened to the several flanges at the edges of the rings. Also the outer ring 95 must be securely carried by the brackets attached to the fan blades so that the whole series of rings may move as one with the fan blades in their rapid rotation.

A water or liquid reservoir 18 is shaped 100 to conform to the motor casing and to be supported thereon with the bottom of the reservoir very slightly above the motor shaft. A pipe or tube 19 with a cock 20 therein to control the flow of water or other liquid 105

leads from the bottom of the reservoir and extends above the motor shaft, this pipe is closed at its outer end but on its under side is perforated by a row of small openings 21 5 which extend along the pipe for approximately its length within the width of the innermost ring.

With the construction as thus arranged water or other liquid is delivered from the 10 pipe upon the motor shaft or within the periphery of the inner ring, and such water or other liquid by the centrifugal force produced by the rapid revolution of the fan is caused to spread within the innermost ring 15 and to be forced as a fine spray through the perforations of the ring. Such spray is in turn collected on the inner face of the next outer ring and again forced as a fine spray through the perforations of the ring, and 20 this operation is repeated for the series of rings until the outer ring is reached. By this means a fine mist or fog is maintained between each pair of rings of the series, and the air current caused by the fan is drawn 25 through such areas of mist or fog taking up the fine particles of the same, so that the air as delivered from the fan may be brought to any desired condition of humidity. In addition to the humidity thus obtained the air current causes the rapid 30 evaporation of the fine liquid particles with the consequent absorption of heat thus producing a cooling of the air and the mist and also of the several rings, and as the liquid 35 spray is cooled progressively as it passes through the series of rings from the inner ring to the outermost a final cooling is secured of the spray as it is collected within the outer ring which may if desired bring 40 such mist or spray very nearly to the condition of a fine frost or snow.

I am aware that it is not new to project a fine spray of water or liquid into an air current, also that devices have been constructed which employ the centrifugal force of rotating parts to throw the liquid spray into the air, but I believe that it is broadly new to provide means for collecting the spray after it has been subjected to the cooling produced by the evaporation of some 50 part of it in an air current, and to successively repeat the operation to secure a progressive cooling of the liquid, also to make use of such cooled spray to reduce the temperature of air.

If the device as described is operated at that speed and under such conditions as to produce a fine snow or frost within the confines of the outermost ring, it is only necessary to operate the same until the snow or frost fills the outermost ring and then to remove such snow from the ring by means of a spoon or proper scraper, but as the device will more often be employed simply for 65 cooling and moistening the air current sup-

plied by the fan and also for the cooling of a water supply, the construction is preferably provided with means for collecting and receiving the cooled liquid as it accumulates in the outer ring. For such purpose the 70 outer ring is formed with the central channel or groove 12 in which the cooled liquid accumulates as it is condensed from the fine mist thrown through the perforations in the outermost of the perforated rings 15^c. To 75 provide for the discharge of the liquid from the channel 12 in the outer ring, the bottom of such channel is perforated by a row of small openings at desired places in the ring two of such rows of perforations being 80 shown. A valve comprising a plate 22 preferably with a facing of cork or leather 22^a is secured on a small shaft 23 mounted in the sides of channel 12, this shaft extends at one end beyond the side of the ring and is bent 85 inward to form the arm 23^a which carries at its end a bearing roller 24, a spring 25 is coiled around the shaft 23 engaging at one end with the ring and at its other end with the arm 23^a so as to hold the plate 22 down 90 to close the perforations in the ring. A cam plate 26 is secured on the wire guard in position to be engaged by the roller 24 as the ring is revolved to throw the arm outward to effect the elevation of the plate 22 at which 95 time the liquid in the channel is discharged through the perforations into a receptacle placed to receive the same. Such receptacle 27 is of any suitable material as metal, rubber or the like and comprises an inclined 100 rear wall 27^a and curved sides 27^b the sides curving inwardly toward the wall, the whole in cross section appearing shaped as the numeral 6, the receptacle being placed so that liquid discharged from the ring is driven in 105 between the curved sides striking against the rear wall and trickling downward to the ends of the receptacle. Pipes 28 lead off from the ends of the receptacle and conduct the liquid back into the reservoir 18 mounted 110 on the motor casing thus a supply of cool water or other liquid is maintained in the reservoir, the liquid if water kept sufficiently cold so as to obviate all necessity for ice if used for drinking purposes.

While so shown, however, it is obviously not essential that the bottom of the reservoir should be above the motor shaft but it may extend below and the water may be delivered from the pipe 19 on the interior of the inner 115 ring 15 below the motor shaft.

A modification of the collecting receptacle and outer ring is shown in Fig. 5, in which the channel 12 of the ring is perforated throughout its extent and no valve controls 120 the perforations, the liquid as thrown from the ring being received into an annular receptacle 27' of the same shape in cross section as the receptacle 27, but completely encircling the ring, the collected moisture 125

draining down to the lowermost point of the receptacle and being carried off by a pipe 28' to any desired reservoir or place. Such modification may be preferably employed 5 if the fan is placed to rotate in a horizontal plane, or if mounted so as to be adjustable as shown in Fig. 6.

The air and liquid conditioning device may be applied to a fan mounted on a shaft 10 rotated by any means, in place of the motor illustrated, such as a belt, gearing, etc.

The number of rings may be varied in number and width to vary the amount of mist or spray through which air is forced, 15 or a ring or rings may be made wider than the other rings, or the series may be constructed of rings of increasing or decreasing width respectively from the center outwardly. A variation may also be made in 20 the width and depth of the corrugations in the different rings, and likewise the size of the perforations in the rings may be varied. A plurality of series of rings may also be provided with a single fan or with a plurality of fans.

The device may be used in a room or in an intake passage when built on a larger scale for cooling theaters and other buildings. It may be used to impregnate gas or air with 30 a liquid or a mixture of liquids, or for the purpose of securing an intimate admixture

of different liquids or for emulsifying a liquid, or to homogenize a fluid as milk, in which case the perforations in the rings would preferably be of decreasing size from 35 the center outwardly.

Having thus described my invention, I claim:

1. A fan, means for rotating the same, a perforated ring mounted to rotate with the 40 fan and in position to be impinged by the air current thereof, means for discharging a liquid within the ring, and means for collecting the liquid particles discharged through the perforations of the ring. 45

2. A fan and means for rotating the same, a perforated annulus mounted to rotate and in position to be impinged by the air current of the fan, means for discharging a liquid on the interior of said annulus, a second perforated annulus exterior of the first and rotatively mounted and provided with means controlling the discharge through the perforations. 50

3. The construction recited in claim 1, the 55 ring being corrugated in cross section and the perforations being at the bases of the grooves as regarded from the interior of the ring.

In testimony whereof I affix my signature. 60

WILLIAM A. LINDAUER.
